BANDING MACHINE

John H. Mead, Kalamazoo, Mich.

Application September 14, 1944, Serial No. 554,123

8 Claims. (Cl. 81—9.1)

1

This invention relates to banding machines and has to do particularly with an apparatus for applying bands and the like to packages, boxes, bundles, etc.

In the packaging of certain articles it is desirable to use rather strong securing materials which cannot be tied into knots. In applying such materials it is customary to use a seal for securing the ends of the band together. Since such banding materials are often quite rigid, tools are necessary to tighten the band and crimp the seal. Heretofore it has been customary to use separate tools for tightening the band and crimping the seal. The use of multiple tools has the disadvantage of requiring a complex set of apparatus and utilizing several operations to complete the tying operation. Also difficulty has been encountered heretofore with machines of the prior art in severing the spool or coil of unused banding material from the band which has been applied to the package.

An object of the present invention is to provide a simplified means for applying bands to packages.

Another object of the invention is to provide a single tool for applying bands, including tightening, crimping and severing means.

Another object of the invention is to provide an improved tool for tightening a band on an article.

Another object of the invention is to provide an improved tool for banding an article which will not damage the band.

A further object of the invention is to provide a tool that will crimp a seal on a band in such a manner as to insure a firm seal without notching the material of the seal.

A still further object of the invention is to provide a banding tool containing improved means for cutting the band from the supply coil after the band is sealed.

A banding operation usually comprises the steps of running a round or flat strip of banding material around an object, tightening the strip around the object, placing a seal on the strip, crimping the seal to form a secure joint and severing the band from the unused portion of the strip.

My invention is intended for use in relatively small scale operations which are performed largely by hand in packaging individual articles. My invention is particularly applicable to banding operations wherein the band and seal are applied by hand prior to the tightening, crimping and cutting operations. Furthermore, my invention is intended for applying soft banding material such as plastic strapping, paper strapping, fibre strapping, reinforced fibre strapping and aluminum strapping. My invention provides means which work remarkably well on plastic

or reinforced fibre strapping materials and has supplied a tool sorely needed in this field.

The tools used heretofore for separately tightening the band and crimping the seal have been fairly successful on steel bands since the banding material is relatively hard, is not damaged by rough handling and may be severed merely by repeated flexing of the band. Such tools, however, have not been successful for use on soft banding materials. Thus, certain tightening machines operate on the principle of a revolving gear that moves the band by biting into it. With steel banding this action causes only light, unimportant indentations. But in the case of soft bands, the teeth dig into the banding material instead of moving it as soon as there is any resistance to the progress of the band through the machine.

Also, crimping machines used heretofore on steel banding produce a secure joint by notching both the seal and the band to keep the strap from slipping out of the seal. Such crimping cannot be used with soft banding materials which are weaker than steel and notching would impair the minimum strength required for even very light applications. Moreover, soft materials do not have the necessary rigidity to prevent the band from slipping through the seal even though notched.

In accordance with the present invention, I have provided a single tool which is relatively simple and eminently successful for use on soft banding materials, although it may be used on more rigid bands such as steel bands. The tool of the present invention comprises means for tightening, crimping and severing the band, which means cooperatively function to apply the band in a simple, efficient and more facile manner than accomplished heretofore with prior art tools.

The invention will be more fully understood from the following description read in connection with the accompanying drawings, wherein:

Figure 1 shows a portion of a box with the band and seal in position for applying the tool.

Figure 2 shows the manner in which the tool is hooked on to the unused portion of the strap in order to bring the tool to bear against the seal for tightening.

Figure 3 shows the tool in a horizontal position ready for tightening the band.

Figure 4 shows the tool in a vertical position to which it has been raised to tighten the strap sufficiently.

Figure 5 shows the tool in position for crimping the seal and cutting the strap.

Figure 6 is a front view of the head of the tool showing in detail the cutting means.

Figure 7 is a side view of the crimping and cut-

ting head showing the crimping and cutting means in an open position.

Figure 8 is a section of the crimping and cutting head taken along the line 8-8 of Figure 7 in the direction of the arrows.

Figure 9 is a sectional view similar to that in Figure 8 with the crimping jaws in a closed position.

Figure 10 is a bottom view of the tool showing the crimping jaws in an open position.

Figure 11 shows a modified form of cutter arrangement.

Figure 12 shows diagrammatically the shape of the seal after crimping.

Referring to the drawings, particularly Figures 6 to 10, the tool comprises a head represented generally by the numeral 15. The head is constructed of two parallel plates 16 secured in spaced relation by the bolts 18. Secured to and extending upward from the top of the rear plate is a frame 20 for holding a tightening lever 21 pivotally mounted thereto and which is adapted to swing on the top of the frame as a fulcrum as illustrated in Figures 2 to 5, inclusive. The lever 21 is fitted with a groove 22 for receiving the strap to be tightened. Positioned between the walls 16 is an anvil 24 which is secured to the walls by a bolt 25. The lower end of the anvil is positioned a small distance upward from the bottom of the plates 16 is provided with a ridge 27 in order to provide an offset crimping surface as explained more fully hereinafter. Also located between the walls 16 is a pair of crimping jaws 28 which are hinged on the lower bolts 18. The crimping jaws are provided with teeth portions 30 which cooperate with the anvil 24 to crimp the seal. The ends of the jaws 28 opposite the teeth portions are connected by the pins 32 with shoulders 33. The latter are hinged on a pin 36 which operates in slots 37 in the side plates 16. The shoulders 33 are equipped with handles 38. As the handles are lowered and raised the pin 36 slides up and down in the slots 37 whereby the toggle joints are operated to open and close the jaws 28. Attached to the front plate 16 is a housing 40 which is notched in the lower portion to form a hook portion 41. Operating in the housing is a knife 42 which is attached to the pin 36 whereby the knife is actuated by the handles 38 and the toggle joints. The lower cutting end of the knife operates through the recess formed by the notch in the housing 40. As the knife is lowered it passes by the upper portion of the hook 41, causing a shearing action on a band when placed in the notch. The knife and toggle joints are synchronized to form a cooperative action whereby the shearing action of the knife functions simultaneously with the completion of the crimping operation.

The operation of the machine will be better understood by referring to Figures 1 to 5. A strip or band 45 is fitted with a seal 46 and placed around an article such as a box 47, the free end of the band being run through the seal and bent under as shown at 50 (Figure 1). The unused portion of the band is next inserted in the recess in the knife housing 40, drawing it over the hook portion 41 (Figure 2). The head 15 is lowered to a horizontal position and the hook 41 is forced between the overlapping bands against the seal. The strip is then placed in the groove 22 of the lever 21 while the tool is in a horizontal position. The band is drawn tightly over the end of the lever 21 while the bottom of the tool is brought against the seal (Figure 3). The band is drawn

tightly over the end of lever 21 and the tool is now raised to a vertical position (Figure 4) the handles 38 dropping to a crimping position. After the band is sufficiently tightened, the handles 38 are forced upwardly, causing a crimping of the seal and a cutting of the unused portion of the band (Figure 5).

An important feature of the present invention is the synchronized action of the cutter with the crimpler. The use of the toggle pin as an actuating element for the knife creates a cooperative action between the knife and crimpler to create an important contribution in this art.

The cutting hook 41 may consist of a straight edge for the shearing surface, although I contemplate using an auxiliary part such as a pin 55 (Figure 11) located slightly above the shearing surface 41 and over which the band is threaded. The pin 55 is fastened to the rear of the housing 40. In this arrangement the cutting knife is cut away at the end, causing a protruding section 56 which on lowering the knife not only cuts the band but also bends the cut end down to avoid the exposure of a sharp end of the band. This feature has the advantage in the case of soft metal banding or steel re-enforced banding that the severed stub is bent downward, thus minimizing the possibility of the operator being scratched by the sharp edge of the stub.

The front and rear plates 16 are notched at the bottom to form recesses 58 (Figure 6). The seal rests in these notches during the crimping operation. The jaws 28 press on the seal and force it to conform to the shape of the anvil 24. The anvil causes a deep depression in the middle of the seal running entirely across its width. The contour of the seal after crimping is shown in Figure 12. The jaws afford resistance which permits the ridge of the anvil to create the recession. The relationship of the notches to the anvil is an important element in the sealing operation. The plates project beyond the base of the anvil thus giving a sharp downward bend to the ends of the seal. The downward bend is important since it changes the direction of the pull of the band from a right angle to the depression to a much greater and more favorable oblique angle. This type of seal has been found to be extremely secure for soft materials.

The tightening element comprising a lever affixed to the rear plate in a position to receive the strapping after it has been threaded through the cutting hook produces a cooperative mechanism for quickly and efficiently tightening the band prior to crimping. The tightening operation coacts with the subsequent crimping operation to make the whole performance a unitary operation, particularly as the tool is rolled over into a crimping position during the tightening operation. At the same time, the handles tend to drop into a crimping position and also prevent the band from slipping through the seal.

Obviously, many modifications and variations of the invention hereinbefore set forth may be made without distinguishing from the spirit and scope thereof, and therefore, only such limitations should be imposed as are indicated in the appended claims.

I claim:

1. In a device for securing a band around an article with a seal, the combination comprising a support, a pair of crimping jaws pivotally attached to the support, an anvil disposed between said jaws and rigidly affixed to said support, a toggle joint connecting said jaws, a cutter con-

nected to said toggle joint and slidable on said support, a guide means for said cutter affixed to said support, said guide means being provided with a shearing edge at the lower portion thereof to cooperate with said cutter, said cutter and said jaws being spaced laterally from each other and means to actuate the toggle joint whereby said jaws and cutter are moved in crimping and cutting positions.

2. In a device for securing a band around an article with a seal, the combination comprising a support including a pair of plates having recessed portions therein for the reception of the seal, a pair of crimping jaws pivotally attached to the support, an anvil secured to said plates cooperating with said jaws and interposed between said jaws, a toggle joint connecting said jaws, a cutter connected to said toggle joint and slidable across the face of said support, a guide means for said cutter affixed to said support, said guide means being provided with a shearing edge at the lower portion thereof to cooperate with said cutter, said cutter and said jaws being spaced laterally from each other and means for actuating the toggle joint whereby said jaws and said cutter are actuated in unison and said jaws are brought in crimping position to crimp the seal on the band and against said anvil and said cutter is moved into cutting position to sever said band.

3. A banding tool as described in claim 2 wherein the anvil contains a raised portion to form a depression in the crimped seal.

4. In a device for securing a band around an article with a seal, the combination comprising a support, at least one pair of crimping jaws hingedly mounted on said support, an anvil disposed between said jaws and rigidly affixed to said support, links pivoted together by a pin and also pivoted to the jaw elements, a cutter carried from said pin and being slidably mounted therewith along a predetermined path across the face of the support, a guide means for said cutter affixed to said support, said guide means being provided with a shearing edge at the lower portion thereof to cooperate with said cutter, said cutter and said jaws being spaced laterally from each other, and means to actuate the links for simultaneously actuating the cutter and crimping jaws in unison, the pivoted links being adapted to close the jaws and to crimp the seal and to move the cutter downwardly when moved in one direction and to open the jaws and to move the cutter upwardly when the links are moved in an opposite direction.

5. In a device for securing a band around an article with a seal, the combination comprising a support, a guide means secured to said support, said guide means containing a recessed portion in the lower end thereof providing a shearing edge, at least one pair of crimping jaws hingedly mounted on said support, an anvil disposed between said jaws and rigidly affixed to said support, a pair of links pivoted together by a pin and also pivoted to the jaw elements, a cutter carried from said pin, said cutter being slidably mounted for movement in said guide means, said cutter and said jaws being spaced laterally from each other, and means to actuate the links for simultaneously actuating the cutter and crimping jaws in unison, the pivoted links being adapted to close the jaws and to crimp the seal and to move the cutter downwardly to sever the band when moved in one direction and to open the jaws and to move the cutter upward when the links are moved in an opposite direction.

6. A banding tool as described in claim 5 wherein a second pin is affixed to the guide means and wherein the cutter is cut away at its lower end to cooperate with said second-mentioned pin whereby the severed portion of the band is bent downwardly.

7. In combination with a banding tool for securing a band around an article with a seal, including a support, a pair of crimping jaws pivotally attached to the support, an anvil disposed between said jaws and rigidly affixed to said support, a toggle joint connecting said jaws, a cutter connected to said toggle joint and slidable on said support, a guide means for said cutter affixed to said support, said guide means being provided with a shearing edge at the lower portion thereof to cooperate with said cutter, said cutter and said jaws being spaced laterally from each other, said tool including means to actuate the toggle joint whereby said jaws and cutter are moved in crimping and cutting positions; a band tensioning means comprising a lever pivotally mounted on said support, a groove in the end of said lever adjacent its pivotal mounting for threadedly engaging the free end of the band strapping to be severed, the pivotal mounting of said lever serving to tighten the band when the band is manually drawn thereover and to lift the support from a horizontal to a vertical position.

8. The combination in a banding machine for securing overlapping strap ends, of a pair of side plates, a pair of jaws pivotally mounted between said plates for movement from and towards each other, said jaws being adapted to receive between them an open seal embracing overlapping strap ends, an anvil disposed between said jaws and rigidly affixed to said plates, jaw actuating levers having toggle joint connections with said jaws, a cutter connected to said toggle joint, a guide means secured to one of said plates, said cutter being slidably mounted for movement in said guide means and across the face of said plate, said guide means containing a recessed portion in the lower end thereof providing a shearing edge cooperating with said cutter, said cutter and said jaws being spaced laterally from each other, said jaws being adapted upon movement of said jaw actuating levers to bend said seal about said overlapping strap ends and to force said seal against said anvil for crimping said seal over said overlapping strap ends, said levers simultaneously lowering said cutter to sever the unused portion of said strap.
